STRIP FEEDING APPARATUS

Stanley L. Nowelsky, Belleville, N. J.

Application January 24, 1948, Serial No. 4,095

13 Claims. (Cl. 271—2.5)

1

This invention relates to means for feeding strip metal stock to a punch press and has many advantages over prior art structures for this purpose. It is one of the objects of my present invention to provide a feeding structure which will require a minimum time for setting up the structure on a press including the setting for length of stroke or for thickness of material.

Another object is to provide a feed structure in which spring overthrows are provided to permit certain variations in the setting up operations without injury to the structure.

Another object of my invention is to provide automatic compensation for wear in the feed slide and its track. A further object is to provide automatic braking of the slide and hence prevention of slipping of the slide during the locking cycle and insure accurate feeding at all times. A further object is to provide an apparatus which is reversible in position on its sub-base so as to permit the stock to be pushed or pulled through the press.

A still further and important object is to provide a stock feeding structure for punch presses that is simpler and cheaper than those heretofore proposed.

These and other objects will be readily perceived by one familiar with structures of this kind by reference to the following specification taken with the annexed drawings wherein:

Figure 1 is a plan view of the structure.

Figure 2 is a side elevational view of Figure 1, the parts being shown about half-way on the forward stroke.

Figure 3 is an end view of Figure 2 looking from right to left without the stock.

Figure 4 is an end view of Figure 2 looking from left to right without the stock.

Figure 5 is a central longitudinal view of Figure 1 but showing in full the control rod and springs carried thereon, the parts being shown about half-way on the return stroke.

Figure 6 is a view of the line 6—6 of Figure 2.

Figure 7 is a part sectional and elevational view across the slide in front of a modified form of lock means for gripping the stock.

Figure 8 is a fragmentary view on the line 8—8 of Figure 7.

In the drawings wherein like numbers refer to corresponding parts, 1 is a support plate having holes 2 for fastening it to the bed plate of the press. Fastened to the plate 1 as by cap screws 3 is a base member 4. Extending upwardly from opposite sides of the base members 4 are standards 5 and 6. Fastened at the upper ends of

2

these standards by screws 59 is a shaft 7 and rotatably carried on this shaft is a lever 9 having an arm 10 adapted to be connected to a press operating member and an arm 11 terminating in a spherical end 12, that is located between a pair of collars 13 and 14, each positioned on and held to an operating member on rod 15 in any satisfactory manner as by a dowel pin 16. The double arm lever 9 is centrally positioned between the standards 5 and 6 by spacing tubular members 18 and 19 and provided with a lubricating member 8. The rod 15 also carries, in a similar manner, a collar 17.

The rod 15 has one end supported in a bar 20 that is fastened in any satisfactory manner to extension 21 of the standards 5 and 6. The opposite end of the rod 15 is supported by the outer end 22 of a feed slide 23. The end 22 may be fastened to the feedslide or made an integral part thereof.

Freely positioned between the collars 14 and 17 on the rod 15 is a locking device 24 operatively held in place by spiral springs 25 and 26 which encircle the rod 15 and have their outer ends 27 abutting against the stops collars 14 and 17 while their inner ends engage cup and cone type washers 28 that contact with opposite sides of the lock member 24, the spring 25 serves when force is applied to lever 9 to tilt or rock lock member 24 that is pivoted at 29 to opposite upwardly extending sides 23, so that its somewhat rounded end 30 will clamp the stock and move it forward to the press. When the slide 23 reaches the full end of its forward stroke as determined by the lever 9 and the return movement is started, the spring 26 acts on the lock member 24 to tilt it in reverse direction and causes the end 30 to be released from the stock. Coincident therewith an eccentric lock 31 pivotally mounted on a pin 32 carried in frame members 33, is caused by spring 34 to move into locking engagement with the stock to prevent its shifting backwardly. The spring 34 is carried somewhat freely on an adjustable stud 35 that is carried by a frame member 36 as will be seen by reference to Figure 5. Slide rails 37 and 38 fastened to parts of the base member 4 in any satisfactory manner as by cap screws 39, have at the stock entering end of the structure, members 40 and 41 each having a slot 42 to receive a locking stud that engages a clamping washer to hold the members 40 and 41 in adjusted position. On the inner ends of each member 40 and 41 is mounted a double row ball bearing 53. These bearings engage the edges of the

stock and thereby guide and assist in passing the stock through the apparatus.

Adjacent the members 40 and 41 is a brace rod 45 fastened to the extremities of the slide rails 31 and 38 as by cap screws 46. The slide rails 31 and 38 have inwardly projecting ledges 47 and 48 which engage co-operative portions of the slide 23 over flat bearing surfaces of considerable area.

A very important feature of this invention is the use of a pair of laterally spaced gibs 49 and 50 located in opposite parts of the base member 4 relatively close to the edges thereof so as to be approximately below the sides of the slide which carry the feed lock. These gibs are pressed against the bottom of the feed slide by similar springs 51 at opposite ends of the gibs, the tension of the springs is controlled by screws 52. Preferably the gibs 49 and 50 are made of material different from the base of the slide, such as bronze. These gibs apply to the slide continuous and uniform braking action and provides automatic compensation for wear at the areas 47 and 48 and thereby prevents its slipping and insures accurate feeding of the stock at all times.

The slide has a centrally located boss 53 which is adapted to engage adjustable stop screws 54 and 55 which are set to co-operate with springs 25 and 26 that also act to take up motion of the press arm connected to the arm 10 of lever 9. This means that the press may be operated with a crank arm instead of a cam which is usually used to provide a dwell while the press punch is going through the stock. The springs 25 and 26 also provide a safety feature in being able to take care of errors in setting up the apparatus. An adjustable stop 56 is carried by the slide to limit the movement of the feed lock 24 during the return movement of the slide and also to adjust the lock 24 to take care of stocks of different thickness. Lock 31 is likewise adjustable to take care of such stocks.

In Figures 7 and 8 I have shown a modified form of feedlock 57 wherein the stock engaging end is provided with a plurality adjustable set screws 58 which are adapted to engage stock, having a high finish, at points which will be on the scrap and not on the punched out part. A similar construction should be used on the lock corresponding to 31. Other variations in the details may be utilized without departing from the scope of the appended claims.

What I claim is:

1. Stock feeding means for a punch press including, a support plate for attachment to the press, a base member fastened to said plate and having spaced guide members fastened thereto, a pair of spaced longitudinally extending gibs carried in the base member, a feed slide held in place by said guide members and having a bottom portion resting on said gibs, the slide having oppositely disposed side parts extending above its bottom portion, a stock gripping cam pivotally mounted between said slide parts, an operating rod supported at opposite ends of the slide and passing through the upper portion of said cam which is oscillatable thereon, compression springs carried by the rod in fixed position thereon, one on each side of the cam end and engaging it, means operating on the rod adjacent one of said springs and co-operating therewith for moving the rod to cause the cam to move into stock gripping position, the other of said springs co-operating with the rod after the end of the for-

ward movement of the slide to cause the cam to release the stock and means at the stock entering end of the slide for automatically gripping and holding the stock immediately the forward movement of the slide ends.

2. Stock feeding means as set forth in claim 1 further characterized in that said gibs are spring pressed against the bottom of the feed slide.

3. Stock feeding means as set forth in claim 1 further characterized in that said gibs are composed of material that is different from that of the slide bottom and are spring pressed against the bottom of the feed slide.

4. Stock feeding means as set forth in claim 1 further characterized in that automatically acting but adjustable means are associated with said gibs for compensating for wear between them and the slide.

5. Stock feeding means as set forth in claim 1 further characterized in that said means at the stock entering end of the slide includes, an adjustable cam lock to function with various thicknesses of stock with oppositely disposed adjustable anti-friction bearing rollers for guiding the stock into the slide.

6. A stock feeding means for a punch press including a feed slide with guide members positioned exteriorly and on opposite sides of the slide, the slide having an upwardly extending end and an operating rod supported in part by said end, a feed cam lock pivoted at its opposite edges to the slide, said rod passing freely through the upper part of said cam, spring overthrows carried on said rod so as to apply pressure to opposite sides of said cam, means for actuating the slide by first acting on said rod adjacent the end of one of said springs overthrows to cause said cam to move into locking engagement with the stock and thereby move it and the slide forward to the end of its stroke, the other of said springs then acting on the cam to release it from the stock and an adjustable cam lock at the stock entering end of the slide for gripping and holding the stock on the return movement of the slide.

7. A stock feeding means as set forth in claim 6 further characterized in that means are provided for preventing said slide from slipping during the stock locking cycle.

8. A stock feeding means as set forth in claim 6 further characterized in that said slide rests on automatically acting gibs to provide continuous braking action on the slide.

9. A stock feeding means for a punch press including a feed slide held on opposite sides between guide members, a single centrally located operating rod carried by the slide at one end, with means for actuating the rod, a feed lock pivoted to opposite sides of the slide but extending upwardly so said rod passes freely therethrough, springs held in operative position on the rod, one on each side of the feed lock and engaging it so as to resiliently apply to the feed lock, the motion applied to the rod, an eccentric lock at the stock entering end of the slide for automatically gripping and holding the stock on the return movement of the slide.

10. A stock feed means as set forth in claim 9 further defined in that one end of each spring engages the feed lock through the medium of a cup and cone type washer.

11. A stock feeding apparatus for a punch press including, a base, slide rails carried by the base on opposite sides thereof with inwardly projecting ledges of considerable surface area and

directly engaging the slide in vertical and horizontal directions, a feed slide having its edges engaging the inner horizontal and vertical surfaces of said ledges, and also having upwardly extending sides and one end, an operating rod having one end freely carried in said slide end, a frame member for slidably supporting the other end of said rod, a feed lock pivoted to the sides of the slide and having a clearance hole for said rod, springs operatively located on the rod, one on each side of and acting against the lock, resiliently actuated gibbs located in the base on opposite sides thereof and acting on the slide preferably under its sides, a spring actuated lock for engaging and holding the stock on the return movement of the slide and anti-friction means at the stock entering end for guiding the stock onto the slide.

12. A stock feeding structure for a punch press including, a base having laterally spaced spring pressed gibbs therein, a slide carried by the base and having a bottom portion resting on said gibbs, slide rails carried by the base on opposite sides thereof and having ledges extending inwardly over upper surface portions of the bottom of the slide, an operating rod supported at one end by a frame member of the structure while its opposite end is supported by a part of the slide, a feed lock supported by both the slide and the rod, springs operatively located on the rod, one on each side of and acting against the lock and an automatically acting lock for engaging and holding the stock from slipping on the return movement of the slide.

13. A stock feeding means for a punch press including a base member carrying guide members, a feed slide held on its opposite sides between said guide members, a single centrally located operating rod carried at one end by said slide with means for actuating the rod, a feed cam lock pivoted to opposite parts of the slide but operatively connected to said rod by compression springs located one on each side of the cam lock and positioned between it and stop members fastened to said rod, means at the stock entering end of the slide for automatically gripping and holding the stock just before the slide starts back on its return movement and a pair of oppositely disposed spring pressed gibbs located so as to apply a continuous beaking action on the slide approximately below said opposite parts of the slide.
